UNITED STATES PATENT OFFICE.

VAUGHN E. MORRISON, OF DETROIT, MICHIGAN, ASSIGNOR, BY DIRECT AND MESNE ASSIGNMENTS, TO MORRISON LABORATORIES, INCORPORATED, A CORPORATION OF MICHIGAN.

TELEPHONE-RECEIVER UNIT.

Application filed February 3, 1923. Serial No. 616,681.

To all whom it may concern:

Be it known that I, VAUGHN E. MORRISON, a citizen of the United States of America, residing at Detroit, in the county of Wayne and State of Michigan, have invented certain new and useful Improvements in Telephone-Receiver Units, of which the following is a specification, reference being had therein to the accompanying drawings.

10 This invention relates to instruments for making audible, electrically transmitted messages, and more particularly to those instruments known as telephone receivers and which embody a diaphragm or the like operated by an electro-magnet under the influence of current variations.

It is a well known principle of operation of a magnet that its field strength or attractive pull upon its armature varies inversely as the square of the distance between its pole and armature, and in telephone receivers as commonly constructed, this distance between terminal or magnet pole and armature or diaphragm is fixed in the construction of the phone, that is, magnet and diaphragm are not relatively adjustable to vary the air gap.

The object of the present invention is to provide an adjustment whereby the normal distance or air gap between magnet pole and diaphragm or other armature may be varied to vary the influence of the magnet upon the diaphragm for the purpose of securing best results in use of the phone under the influence of electrical currents having different energizing effects upon the electro-magnet.

A further object is to provide a simple and efficient construction having certain other new and useful features, all as herein-after more fully described.

With the above and other ends in view, the invention consists in the several matters hereinafter set forth and more particularly pointed out in the appended claims, reference being had to the accompanying drawings in which

Fig. 1 is a plan view of a common form of telephone receiver with its cap or cover removed;

Fig. 2 is a transverse section of the receiver shown in Fig. 1, with its cap in place and embodying adjusting means, the con-

struction being illustrative of an embodiment of the present invention;

Fig. 3 is a view similar to Fig. 2 and showing a modified construction particularly adapted for use in conjunction with an amplifying horn or the like;

Fig. 4 is a transverse section through the casing of a receiver showing interior mechanism in elevation and illustrating a further modified construction;

Fig. 5 is a sectional view similar to Fig. 4 showing a modification thereof; and

Fig. 6 is a similar view illustrating a further modification of the construction.

In the drawings, a common arrangement of diaphragm and electro-magnets is shown, but it will be understood that the present invention may be embodied in other forms and constructions of receivers where an electro-magnet or magnets is employed to effect, through variations in the magnetic pull, movements of the diaphragm to reproduce the sound of the transmitted message.

When the transmission of messages is effected by radio or other means operating with comparatively small current, it is particularly advantageous to have a very sensitive receiver so that the diaphragm will be operated by the smallest current impulses passing through the magnetic coil to accurately reproduce all of the transmitted sounds; and as the magnetic pull exerted on the diaphragm is proportioned to the square of the magnetic field strength, and as the pull exerted on the magnet armature varies inversely as the square of the distance between the armature and the pole of the magnet, by varying this distance or air gap the influence of the magnet upon the armature or diaphragm is varied. Therefore if it is found that the received current is smaller than the receiver was designed to be efficiently operated by, a very slight adjustment of the magnet and armature toward each other, will give an increase of magnetic pull upon the armature sufficient to make the receiver efficiently operative with the reduced current. Likewise an increase in the air gap will make the receiver operate efficiently with larger current than it was designed to be most efficiently operated by.

In radio broadcasting, the strength of the received current impulses depends primarily

upon the sending apparatus and the distance from the sending station at which the transmitted message is received and as the radio energy output varies from time to time and as atmospheric and other conditions may vary the strength of the received current impulses, it is obvious that it is highly desirable to provide means for varying the sensitiveness of the receiver in order to meet these slight variations in strength of current impulses received.

In the drawings, the simplest and most common construction of receiver is shown as an illustration of an application of the invention, and variations of this simple construction are shown to illustrate various ways of constructing this type of receiver to effect an adjustment of magnet and armature relatively. The construction shown in Fig. 1 and 2 comprises the usual casing 1 within which is mounted a plurality of superposed permanent magnets, or a magnet formed of a plurality of permanently magnetized metal strips secured together to form a magnet 2 of the horse-shoe type, with pole pieces 3 upon which are wound coils 4 connected in series in the incoming or message transmitting circuit. The usual cap or ear piece 5 is screw-threaded upon the casing to close the open side thereof and a flexible diaphragm 6 or metal disk is positioned within said cap with peripheral portion clamped between the edge of the annular wall of the casing, and the cap to hold said disk positioned adjacent to and spaced slightly from the pole pieces of the magnets and to be flexed by the attractive force of the permanent magnet and by the influence thereon of current passing through the coils 4, to reproduce (in the usual manner) the sounds of the transmitted message and make the message audible through the central opening 7 in the cap or ear piece 5.

To provide for an adjustment of the diaphragm which forms an armature for the magnet, and the pole pieces 3, relatively, to vary the air gap and thus vary the pull of the magnet upon the diaphragm, rings or annular strips 8, of yieldable, compressible or resilient material are interposed, one between the peripheral portion of the diaphragm, and the edge of the casing wall and the other between the diaphragm and the cap so that by screwing the cap upon the casing, these rings will be compressed and the diaphragm thus adjusted toward the pole pieces. By a rotation of the cap upon the casing, a very accurate and minute adjustment of the diaphragm may thus be secured by very simple means applicable to receivers as commonly constructed.

In Fig. 3, a construction of receiver is shown which will provide a very fine and accurate adjustment of diaphragm, and which is such as to make the receiver par-

ticularly adaptable for use with an amplifying horn.

In this construction, the casing 1 is fitted to slide within a shell comprising an annular ring or wall 9 provided with a closure plate 10 at one end having central openings 11 to permit the sound waves to escape and is closed at its opposite end by a screw-threaded closure 12 having a central aperture in which is mounted a stud or boss 13 having an axial screw-threaded bore to receive an adjusting screw 14 having a knurled head at its outer end and adapted to bear at its inner end against the end wall of the casing 1 at the axis thereof. A lock nut 15 is also provided on said screw to engage the closure and lock the screw in any position to which it may be adjusted. A horn carrying cap 16 is in screw-threaded engagement with the end of the shell having the closure plate or disk 10, and this cap has a central opening within which the end of a suitable amplifying horn 16 may be secured.

The diaphragm 6 is clamped at its periphery between the end edge of the annular casing wall and the plate 10 with the compressible rings 8 interposed, and thus by turning the adjusting screw 14 the casing 1 may be adjusted within the shell ring 9 toward the plate 10 and thus compress said rings 8 to a greater or lesser extent and moving the diaphragm and magnet pole pieces relatively.

A similar relative adjustment of diaphragm and pole pieces may be secured by means of the construction shown in Fig. 4 wherein in the casing 1 is inclosed within an outer shell as in Fig. 3 and adjustment of the casing is secured through the provision of an adjusting cap 17 having an annular flange in screw-threaded engagement with external screw threads on the shell, and a ring 18 is interposed between said cap 17 and the bottom of the casing 1 to force the casing to move toward the diaphragm when the adjusting cap is turned and thus adjust the pole pieces and diaphragm relatively.

A construction very similar to that shown in Fig. 4, is shown in Fig. 5, the only difference being in the substitution of a central stud 19 on the adjusting cap 17 for the ring 18, said stud engaging the bottom wall of the casing 1 at the axis thereof to move the casing, instead of said casing being engaged adjacent the periphery of said wall by said ring.

In the construction shown in Fig. 6 the bottom wall 20 of the casing 1 is made comparatively thin so that it will spring or yield under pressure and by providing a closure similar to the closure 12 shown in Fig. 3, for the outer shell, and the adjusting screw 14 for engaging the bottom wall 20 at the axis thereof, this wall may be flexed by turning the screw, and, as the magnet is carried by

said wall, said magnet will be moved toward the diaphragm which is clamped solidly at its periphery between the end edge of the annular wall of the casing and the end wall 5 of the shell.

In the several figures are therefore illustrated various ways of accomplishing a certain result, to wit, the relative adjustment of diaphragm and magnet poles to vary the air 10 gap, and the object attained through such adjustment may also be attained in connection with other types and constructions of telephone receivers, the relative adjustment of magnet or magnets and member or members attracted or repelled thereby to reproduce sound through diaphragm vibration, being contemplated.

Having thus fully described my invention, what I claim is:—

20 1. A device of the character described comprising a casing having an open side, a shell within which the casing is slidable, an electro-magnet mounted within the casing and provided with pole pieces directed toward the open side of the casing, a diaphragm supported across the open side of the casing and adjacent the pole pieces and free from engagement with the shell, an apertured cover plate secured to the shell 25 and arranged to limit movement of the diaphragm in one direction, resilient means arranged between the diaphragm and casing, and means carried by the shell for moving the casing to compress the resilient 30 means and so adjust the pole pieces toward the diaphragm.

2. A device of the character described comprising a cup-shaped casing, an electro-magnet mounted in the casing and having pole pieces projecting toward the open side of the casing, a shell enclosing the casing and within which the casing is slidable, a diaphragm mounted across the open side of the casing and free from engagement with the shell, an apertured cover plate secured on the shell and arranged to limit movement of the diaphragm in one direction, a resilient ring member interposed between the annular edge portion of the diaphragm and the annular end face of the wall of the casing, and adjusting means carried by the shell for moving the casing within the shell to compress the resilient ring and so adjust the diaphragm and pole pieces relatively.

3. A device of the character described comprising a casing having a bottom wall and an annular side wall, a shell enclosing the casing and within which the casing is slidable, a diaphragm across the open side of the casing, an electro-magnet mounted in the casing and having pole pieces directed toward the diaphragm, and free from engagement with the shell, an apertured cover plate secured to the shell and arranged to limit movement of the diaphragm in one di-

rection, resilient means arranged between the diaphragm and casing, and an adjusting screw carried by the shell and engaging the bottom wall of the casing at the axis of the casing for adjusting said casing within the shell to adjust the diaphragm and pole pieces relatively.

4. In a device of the character described, the combination of an inner cup-shaped casing, an outer shell enclosing the casing and within which the casing is slidable, an electro-magnet mounted within the casing upon the bottom wall thereof and having pole pieces directed toward the open end of the casing, a diaphragm within the shell extending across the open side of the casing, a resilient rubber ring interposed between the shell and the edge portion of the diaphragm, an apertured cover plate secured on the shell, a second rubber ring interposed between the annular edge portion of the diaphragm and the cover plate, said rubber rings being formed with flat side surfaces to engage and lie flat upon the sides of the diaphragm throughout the entire edge portion thereof, and an adjusting member carried by the shell and engaging the casing to slide the casing within the shell and compress the rubber rings to clamp the diaphragm and to adjust said diaphragm and pole pieces relatively.

5. A device of the character described comprising an inner cup-shaped casing having an annular side wall and a bottom wall, an electro-magnet secured within the casing upon the bottom wall thereof and having pole pieces directed toward the open end of the casing, a shell enclosing the casing and within which the casing is slidable, a diaphragm extending across the open side of the casing and free from engagement with the shell, and a thumb screw extending through the end wall of the shell and engaging the bottom wall of the casing for adjusting the casing within the shell.

6. A device of the character described comprising a cup-shaped shell having an open side, a casing having an annular side wall slidably fitted within the shell, an electro-magnet secured within the casing and having pole-pieces directed toward the open side of the shell, a rubber ring resting upon the edge of the annular wall of the casing, a diaphragm resting upon said rubber ring, a second rubber ring resting upon the diaphragm, an apertured cover plate secured over the open side of the shell and adapted to engage the last mentioned rubber ring, and adjusting means carried by the shell for moving the casing within the shell to compress the rubber rings and so adjust the diaphragm and pole-pieces relatively.

7. A device of the character described comprising a cup-shaped shell having an open side, a casing having an annular side

wall slidably fitted within the shell, an electro-magnet secured within the casing, and having pole-pieces directed toward the open side of the shell, a flat resilient ring resting upon the upper edge of the annular wall of the casing, a diaphragm arranged with its outer portion resting upon said resilient ring, a second flat resilient ring resting upon the outer portion of the diaphragm above

10 the first resilient ring, an apertured cover

plate detachably secured on the shell and adapted to engage the uppermost resilient ring, and a rotatable member carried by the shell and engaging the casing to slide the casing within the shell and compress the resilient rings to clamp the diaphragm therebetween and to adjust the diaphragm and pole-pieces relatively.

In testimony whereof I affix my signature.

VAUGHN E. MORRISON.
